Sweden, a corporation of Sweden

Application February 5, 1943, Serial No. 474,872
In Sweden January 16, 1942

3 Claims. (Cl. 274—1)

The present invention relates to an automatic control device for gramophones for obtaining an impulse when a record has been played.

Such an impulse may be utilized either to start a record changing mechanism which places a new record upon the turntable and automatically brings the tone-arm into position to begin the playing of the new record, or to actuate a stopping device which stops the gramophone.

A number of automatic control devices for this purpose are already known. The invention relates to the kind of control devices comprising an oscillating member which tends to actuate a control member but is prevented from this by a blocking member which is adapted to be moved alternately in opposite directions by the oscillating member and by the tone-arm of the gramophone, the arrangement being such that the oscillating member moves the blocking member into an inactive position in which it does not block the oscillating member whereas the tone-arm returns the blocking member to an active position in which it blocks said oscillating member, this return of the blocking member being effected only as long as the reproducing needle of the tone-arm runs through the sound groove of the record but failing to come about when the reproducing needle has entered into a concentric end groove.

According to the present invention a second inactive position is provided for the blocking member into which position the said member is adapted to be moved when the reproducing needle runs through a groove of higher pitch than the sound groove. By reason hereof a control impulse is obtained at an earlier moment with records which are provided with a high-pitch groove connecting the sound groove with the concentric end groove.

The invention is described in the following with reference to the drawing which shows an embodiment of the invention as applied to a gramophone otherwise not shown in detail.

In the drawing 1 designates a shaft upon which the turntable of the gramophone is mounted. The shaft 1 is driven by a motor, not shown. On the shaft 1 there is mounted a gear 2, shown by a dot and dash line. The gear 2 meshes with another gear 3 which is also shown by a dot and dash line. The ratio of gearing between the gears 2 and 3 may suitably be 4 to 1. A cam disc 5 is mounted on the shaft 4 of the gear 3.

An oscillating member consists of an arm 6 which turns on a pivot 7. A pin 8 is secured to the arm 6 and on this pin a roller 9 is pivoted.

A helical spring 10 tends to turn the arm 6 counter-clockwise and to keep the roller 9 in contact with the cam disc 5. Thus, when the cam disc 5 rotates the roller 9 follows its contour, and the right end of the arm 6 performs an oscillating movement.

A control member consisting of a bar 11 displaceable in the direction of its length is arranged near the arm 6 so that it may be actuated by the same and so that a control impulse may be imparted thereto. The bar 11 is connected to a mechanism, not shown, for causing a record change, said mechanism being so arranged that it is started when the bar 11 is moved upwardly. The record changing mechanism may be of any suitable kind.

A blocking member is arranged near the right end of the bar 11, said member consisting of an arm 12 which turns on a pivot 13 at its one end.

10 The other end of the arm 12 is provided with a bent nose 14 and with a short projection 15. The arm 12 is capable of limited movability between two stops 16 and 17.

15 At its right end the arm 6 is formed with a narrow part 18 and with a projection 19 extending therefrom.

20 The arm 12 is actuated by a pin 20 secured to an arm 21 which is coupled by friction to the vertical shaft 22 of a tone-arm, not shown. A stop 23 serves to limit the movement of the arm 21.

25 The mode of operation of the device is as follows: At a certain moment during the playing of a record the members occupy the position 30 shown in the figure. When the shaft 1 with the turntable rotates, the cam disc 5 is turned counter-clockwise. After a complete revolution of the shaft 1 the cam disc 5 has turned through 90° so that the lowest part thereof (that with the 35 smallest radius) faces the roller 9. The spring 10 tends to move the arm 6 upwardly for actuating the bar 11 but is prevented from doing this by the projection 15 on the blocking member 12 which projection is in the path of movement of the projection 19 on the arm 6. Therefore, no actuation of the bar 11 occurs.

40 When the cam disc 5 is rotated through another 90° the highest part thereof (that with the greatest radius) will face the roller 9. Simultaneously the arm 6 is swung downwardly, the right end thereof striking the bent portion of the nose 14 on the arm 12 so that this arm is turned to the right and the projection 15 thereon is moved out of the path of movement of the projection 19.

During the following rotation of the cam disc 5 through $\frac{3}{4}$ of a complete revolution the arm 12 is turned back to the left by the member 21 which is continuously urged clockwise by reason of its frictional engagement with the shaft 22, so that the projection 15 will again be in the path of movement of the projection 19 the next time when the arm 6 is moved upwardly. As will be understood, the shaft 22 of the tone-arm is turned clockwise because the reproducing needle runs in the spiral sound groove of the record.

Thus actuation of the arm 11 does not occur as long as the reproducing needle runs through the normal sound groove.

If, however, the reproducing needle enters a concentric end groove of the record the arm 12 is not returned, and thus the projection 19 is free to pass by the projection 15 to the left thereof and to actuate the bar 11.

If, after the playing of the record, the reproducing needle enters a groove of higher pitch than the sound groove the arm 12 will be turned very quickly to the left under the influence of the member 21. During the time which passes after the arm 6 has been moved downwardly and until it is again moved to its uppermost position the arm 12, therefore, will be turned so far to the left that the projection 19 can pass by the projection 15 to the right thereof and actuate the bar 11. The provision of such a second inactive position for the blocking member 12 is the chief characteristic feature of the present invention.

If the reproducing needle enters an eccentric end groove on a gramophone record, actuation of the bar 11 will take place either in one of the ways described above or the other, depending upon the angular position of the cam disc 5 at which the reproducing needle passes from the sound groove into the eccentric end groove.

Since the angle between the lowest part of the cam disc 5 and the highest part thereof is such as to correspond to one revolution of the turntable 1 (or to a multiple of one revolution) actuation is secured under all circumstances also with a record having an eccentric end groove.

After the record changing mechanism has been started, the soundbox of the tone-arm is raised from the record and the tone-arm is swung outwardly past the edge of the record. Simultaneously the arm 21 is swung counterclockwise until it strikes the stop 23. When the new record has been placed upon the turntable the tone-arm is again swung inwardly until its reproducing needle is above the starting groove of the new record. The pin 20 then again strikes the arm 12, and the above described cycle is repeated when the new record has been played.

What we claim and desire to secure by Letters Patent is:

1. An automatic control device for gramophones having a movable tone arm carrying a reproducing needle for obtaining a control im-

pulse after a record has been played, comprising a pivoted actuator, means for oscillating the same during playing of the record, a control member actuatable by said actuator on completion of playing of a record to produce said impulse, a blocking member movable into positions including an active position blocking movement of said actuator to actuate said control member, and two inactive positions unblocking said movement of said actuator, means on said blocking member engaged by said actuator for moving said blocking member in one direction from the blocking to one of said unblocking positions, and means operated from the tone arm to move said blocking member in the opposite direction into the blocking position as long as the reproducing needle runs through a normal sound groove of the record, and to effect further movement of said blocking member in said opposite direction to said other unblocking position when the reproducing needle runs through a groove of higher pitch than the normal sound groove.

2. A control device according to claim 1 wherein the blocking member is rotatably mounted and provided with a projection obstructing movement of the actuator only when said blocking member is in the active position, and wherein stop means are provided one on each side of said blocking member and spaced therefrom sufficiently to allow rotary movement of said blocking member in either direction from said active position into an unblocking position.

3. An automatic control device for gramophones having a movable tone arm carrying a reproducing needle for obtaining a control impulse after a record has been played, comprising a pivoted actuator, means for oscillating the same during playing of the record, a control member actuatable by said actuator on completion of playing of a record to produce said impulse, a blocking member movable into positions including an active position blocking movement of said actuator to actuate said control member, and two inactive positions unblocking said movement of said actuator, means on said blocking member engaged by said actuator for moving said blocking member in one direction from the blocking to one of said unblocking positions, and means frictionally operated from the tone arm to move said blocking member in the opposite direction into the blocking position as long as the reproducing needle runs through a normal sound groove of the record, and to effect further movement of said blocking member in said opposite direction to said other unblocking position when the reproducing needle runs through a groove of higher pitch than the normal sound groove.
